Primary Examiner — Rosemary K Tarcza*Assistant Examiner* — Yolanda Robinson(57) **CLAIM**

We claim the ornamental design for a topload washing appliance, as shown and described.

DESCRIPTION

FIG. 1 is a first top perspective view of the topload washing appliance of the present invention;

FIG. 2 is a second top perspective view of the topload washing appliance the present invention;

FIG. 3 is a top plan view of the topload washing appliance the present invention;

FIG. 4 is a bottom plan view of the topload washing appliance of the present invention;

FIG. 5 is a first side elevation view of the topload washing appliance of the present invention;

FIG. 6 is a second side elevation view of the topload washing appliance of the present invention;

FIG. 7 is a third side elevation view of the topload washing appliance of the present invention; and

FIG. 8 is a fourth side elevation view of the topload washing appliance of the present invention; and,

FIG. 9 is another first side elevation view of the topload washing appliance of the present invention with the door in an open position to view the underside of the washing appliance door.

The broken lines shown in the figures are for the purpose of illustrating unclaimed portions of the topload washing appliance, and form no part of the claimed design.

The dash-dot broken line(s) define the bounds of the claimed design and form no part thereof.
